UNITED STATES PATENT OFFICE.

HARRY L. OPSAHL, OF MINNEAPOLIS, MINNESOTA.

SPARK-PLUG CARRIER AND TESTING DEVICE.

Application filed January 31, 1921. Serial No. 441,236.

To all whom it may concern:

Be it known that I, HARRY L. OPSAHL, a citizen of the United States, residing at Minneapolis, in the county of Hennepin and 5 State of Minnesota, have invented certain new and useful Improvements in Spark-Plug Carriers and Testing Devices; and I do hereby declare the following to be a full, clear, and exact description of the invention, 10 such as will enable others skilled in the art to which it appertains to make and use the same.

This invention relates to a spark plug carrier and testing device adapted to be secured 15 to an internal combustion engine, preferably on the top of one of the engine cylinders. It is an object of this invention to provide a device in which an extra spark plug can be disposed and in which it will be 20 firmly retained.

It is also an object of the invention to have this extra spark plug carried in such position that it can be readily tested as to its 25 condition and also form testing means for the ignition system.

These and other objects and advantages of the invention will become apparent from the following description made in connection with the accompanying drawings in which 30 like reference characters refer to the same parts throughout the several views, and in which—

Fig. 1 is a view showing a portion of the cylinder head of an engine in section upon 35 which the plug carrying means is disposed, an operative plug also being shown;

Fig. 2 is a top plan view of the spark plug support;

Fig. 3 is a partial plan view of a modification thereof; and

Fig. 4 is a view in side elevation as seen from the bottom of Fig. 3.

Referring to the drawings, the top of an engine cylinder head is shown generally as 1 and the spark plug 2 is shown as screwed in the usual spark plug opening and connected to the cable 3 which is connected with the ignition apparatus. The cable 3 is provided with the usual metal contact clip 4 45 adapted to be secured under the nut 5 of the spark plug binding post.

The present invention comprises a small bracket 6 having an apertured base portion 6^a adapted to be secured to the cylinder head, 50 by being placed under the head of one of the cylinder head bolts. It will, of course,

be understood that separate attaching means may be provided for the bracket if so desired. The bracket extends upwardly and laterally from the base portion 6^a and is provided at its upper portion with an enlarged circular head having opening 7 formed therethrough and a depending flange 8 surrounding said opening. The bracket 6 is designed to be made of brass or other soft metal somewhat softer than the body of the spark plugs. The opening 7 is tapered or converges downwardly and an extra spark plug a is adapted to be carried therein. The plug a will be pressed or jammed down into the opening 7 and given a slight turn when the threads thereon will grip with the sides of the tapered opening 7 and the plug will thus be held firmly in position. The threaded end of a spark plug is ordinarily tapered so that by giving the plug a slight turn a very firm engagement of the threads with the bracket 6 will be obtained.

In the modification shown in Fig. 3, the opening 7' is provided with downwardly and inwardly extended projections 9. The plug will be inserted in the opening 7' in the same manner as described for the opening 7. The tongues 9 will be somewhat resilient and the threads of the spark plug, in addition to gripping the same by turning, will engage slightly over the ends of the same and will thus be firmly held against withdrawal. The same can, however, be quickly removed by a turning movement.

With the extra spark plug disposed, as shown, on the bracket 6, the same will be in convenient position to be withdrawn and be inserted in one of the cylinders if the driver of the car should have trouble with the spark plugs in operation. By loosening the cable 3 the contact piece 4 from the binding post on one of the spark plugs in the cylinders and attaching the same to the extra spark plug, the extra plug can be readily tested, as shown in Fig. 1, since it will be grounded to the engine frame by means of the bracket.

The operation of the ignition can be also tested and ascertained by this manner and the strength of the spark seen by running the engine at different speeds. The bracket therefore, forms a very convenient means for carrying an extra plug, and, as stated, is in the most convenient position for use in testing.

It will thus be seen that applicant has provided an extremely simple and very useful

appliance for an automobile engine and one which has great utility. The extra plug will be firmly carried in the described bracket and will not rattle therein or be jolted out 5 of engagement therewith.

It will, of course, be understood that various changes may be made in the form and proportions of the device without departing from the scope of applicant's invention, which, generally stated, consists in 10 the matter shown and described and set forth in the appended claims.

What is claimed is:

1. A spark plug carrier for an internal 15 combustion engine comprising a thin strip of comparatively soft metal having one of its ends apertured and adapted to be clamped under one of the nuts on a cylinder head bolt, said strip having its other end offset 20 to be disposed above said first mentioned

end and having an aperture therein and provided with integral portions spaced about said aperture and projecting therefrom adapted to receive and hold the threaded end 25 of a spark plug thrust and turned therein.

2. A spark plug carrier for an internal combustion engine comprising a thin strip of comparatively soft metal having one of its ends apertured and adapted to be clamped under one of the nuts on a cylinder head 30 bolt, said strip having its other end offset to be disposed adjacent said first mentioned end and having an aperture therein, spaced integral tangs surrounding said aperture and projecting away from the plane of said 35 latter end, said tangs being adapted to receive and hold a spark plug thrust and turned therein.

In testimony whereof I affix my signature.

HARRY L. OPSAHL.
